Primary Examiner — Keli L Hill*Assistant Examiner* — Harold E Blackwell, II(74) *Attorney, Agent, or Firm* — Burr & Forman, LLP(57) **CLAIM**

The ornamental design for a chalk reel end hook, as shown and described.

DESCRIPTION

FIG. 1 is a perspective view of a chalk reel end hook showing our new design;

FIG. 2 is a top view of the chalk reel end hook of FIG. 1; FIG. 3 is a bottom view of the chalk reel end hook of FIG. 1;

FIG. 4 is a left side view of the chalk reel end hook of FIG. 1;

FIG. 5 is a right side view of the chalk reel end hook of FIG. 1;

FIG. 6 is a front view of the chalk reel end hook of FIG. 1; and,

FIG. 7 is a back view of the chalk reel end hook of FIG. 1. The broken lines in the drawings illustrate portions of a chalk reel end hook which form no part of the claimed design.
